UNITED STATES PATENT OFFICE.

ELOF H. MEDÉN, OF SHORT HILLS, NEW JERSEY, ASSIGNOR TO AMERICAN GASAC-CUMULATOR COMPANY, OF ELIZABETH, NEW JERSEY, A CORPORATION OF NEW JERSEY.

HIGHWAY SIGNAL.

Application filed February 2, 1921. Serial No. 441,740.

To all whom it may concern:

Be it known that I, ELOF H. MEDÉN, a subject of the King of Sweden, and a resident of Short Hills, in the county of Union and State of New Jersey, have invented an Improvement in Highway Signals, of which the following is a specification.

My invention relates to highway signals and it has for its object generally to provide 10 a signal which is adapted to be placed in and along roadways and streets and desired points or positions to afford a means for furnishing information with respect to traffic, road conditions, or any other matter 15 at that particular place. A signal may be employed to indicate danger ahead, such for instance as a railroad crossing, a dangerous turn, the direction of the turn, or the like. It may be employed upon the streets of 20 cities to indicate, among other things, the direction in which traffic shall move at any particular point or place.

A further object of the invention is to provide a single apparatus or device comprising 25 a housing, a lighting means and a signal display head all combined in a self-contained unitary structure.

A still further object is to provide a highway signal device having means whereby it 30 may be employed as an advertising means, the said device thereby constituting a combined signaling and advertising agency.

Other objects and advantages of my invention will be pointed out in the detailed 35 description thereof which follows or will be apparent from such description.

In order that the invention may be readily understood and its practical advantages 40 fully appreciated, reference may be had to the accompanying drawings in which is depicted one convenient form of mechanical embodiment thereof. It will be understood, however, that the invention is susceptible of embodiment in other forms of construction 45 than that shown, and that changes in the details of construction may be made within the scope of the claims without departing from the said invention.

In the drawings:

50 Fig. 1 is a vertical longitudinal sectional view of a highway signal device or apparatus embodying my invention;

Fig. 2 is a view partly in side elevation and vertical section of the upper portion of

the device or apparatus shown in Fig. 1; 55

Fig. 3 is a view in front elevation of the central portion of the signal head showing an opening in which is situated a light concentrating lens;

Fig. 4 is a transverse sectional view taken 60 on the line 4-4 of Fig. 1; and

Fig. 5 is a view in front elevation of the signal head and the upper end portion of the support therefor.

Referring to the drawings: 1 designates a 65 pedestal of concrete or other suitable material upon which the device or apparatus is mounted and to which it is secured.

The said apparatus comprises a housing 70 consisting of relatively stationary side walls 2, the edges of which are secured to angle plates 3 situated at the four corners of the said housing. The fourth side of the housing is closed by means of a door 4 connected at one edge by hinges 5 to an edge portion 75 of one of the angle plates 3. The lower ends of these angle plates are secured to angular anchoring members 6 which in turn are secured to the inwardly extending flange 7 of the base 8 which rests directly upon and 80 is secured to the pedestal 1. The opposite edges of the side wall plates 2 are secured to the flanges of the angle plates 3 by means of rivets 9, as shown. At its upper end the housing is provided with or terminates in a 85 tapering neck portion 10 which is secured to the upper ends of the angle plates 3 by means of angular anchoring members 11. The neck portion 10 is provided adjacent its 90 upper smaller end with an inwardly extending flange 12. 13 designates a flared annular extension projecting upwardly from the upper end of the neck portion 10 which extension is likewise provided with an inwardly extending flange portion 14 which is 95 situated in opposed relation to the flange 12. The flanges 12 and 14 are provided with openings at intervals through which bolts 15 extend for the purpose of securing the flared extension 13 to the upper end of the 100 neck portion 10.

It will be noted that the lower ends of the plates 2 and door 4 terminate a short distance above the upper edge of the base 8, leaving a narrow open space between the 105 said lower ends and the said base.

The open upper end of the neck portion 10 is closed by means of a fine mesh screen

20 situated between the upper end of the neck 10 and the lower end of the extension 13.

The signal light head is secured and 5 mounted upon the extension 13, as is shown. This head comprises a plate 21 of circular formation, as shown, the lower ends of which are connected by means of rivets 22 to opposite edge portions of the extension 10 13. The opposite sides of the circular opening through the circular bent plate 21 are closed by means of plates 23 and 24, the central portions of which project outwardly 15 leaving flanges at the edges thereof as shown. The latter plate, 24, is provided with a central flanged opening 25 which is adapted to be closed by means of a door comprising a frame structure 26 hingedly secured at 27 to the said plate 24. The said 20 door is adapted to be secured in locked position by means of a bolt 28 and locking device 29. A light concentrating lens 30 is supported centrally of the door frame structure 26 to close the central opening 31 there- 25 through. For the purpose of protecting the lens 30 to prevent breaking of the same, protecting rods or bars 33 extend across the opening 30, as shown in Fig. 3.

A transparent or translucent plate 34 is 30 secured to the inner side of the plate 24 and in front of the plate 34 openings are provided through the plate 24 through which light rays from a light within the signal head emerge. These openings may be 35 cut to form letters spelling "Danger", "Curve", etc.; also an opening in the form of a curved arrow may be provided associated with the word "Curve" to indicate the direction of the curve to an approaching 40 automobilist or other traveler. It will be understood that any other information or data desired may in like manner be imparted. A single annular plate 34 may be provided or if preferred a plurality of transparent or translucent plates back of the 45 openings forming the letters, curve, etc., may be provided.

The opening within the door in which the lens 30 is situated is shaded by a hood 35 50 so that the light through the lens will be rendered clearly visible in the day time even though the sun may be shining.

At the upper side of the circularly bent plate 21 an opening 36 is provided which 55 opening is closed by means of a fine mesh screen 37. The said opening and the screen are protected by means of a shield 38 the opposite sides of which are flanged as indicated at 39 and connected to the circularly 60 bent plate 21.

It will be seen that means is provided whereby air may be circulated freely 65 through the housing and the signal head, entering at the bottom of the housing underneath the lower edges of the sides 2

and the door 4 and flowing upwardly there- through and escaping through the opening in the plate 21, or the current may flow in the reverse direction.

The presence of the screens prevents the 70 entry of bugs into the light signal head the presence of which therein sooner or later would interfere with the light.

In order that a suitable light may be furnished for the device or apparatus, I have 75 provided a cylinder 40 which contains gas under pressure, which cylinder rests upon a base 41, of wood or other suitable material. The latter in turn rests upon the pedestal 1. The gas under high pressure, 80 one hundred and fifty to two hundred and seventy-five pounds per square inch, flows from the cylinder 40 through a pipe 42 to a pressure regulator 43, of any known construction, for reducing the pressure of the 85 gas which is supplied to the burners. A pressure gauge 44 having connection with the pipe 42 indicates the pressure of the gas therein. A pipe 45 leading from the pressure regulator supplies a pilot flame while the pipe 46 supplies gas from a flash light 90 device 47 of known construction to supply gas for the light signal flame. The pilot and signal light flames are located within 95 the structure at 50, which is not shown in detail.

When the gas has been exhausted from a cylinder a new cylinder may be substituted therefor or else the same cylinder may be recharged and replaced.

For purposes of economy it is preferred 100 that a flash light apparatus 47 be employed, although it will be understood that the gas may be supplied directly from the gas pressure regulator 43 to the signal light burner, 105 in which case a steady and continuous light would be supplied or provided instead of a flash light. The flash light, in addition to economy, possesses other advantages over a steady light produced by a continuously 110 burning flame. The principal other advantage is that its occurrence at intervals is more likely to attract attention than if it be burning or displayed constantly. A 115 flashing light is more conspicuous and more noticeable than a steady burning flame or light would be.

The sides and the door of the housing as 120 well as the rear of the signal head of the device may be employed for advertising purposes, the advertising data being printed or painted thereon. Advertising data may be substituted for the danger or warning data, previously referred to, upon the 125 front of the signal head.

It will be seen that I have provided a self-contained unitary structure combining in a most practical way both signaling and advertising functions.

Having thus described my invention, what 130

I claim and desire to secure by Letters Patent, is:

1. A highway signal comprising a housing including a base portion at its lower end and a neck portion at its upper end, the sides of the said housing terminating a short distance above the upper side of the said base portion to form a passageway leading into the said housing, and the upper end of the said neck portion being open, a signal head secured to the upper end of the said neck portion, said signal head being provided with an opening in its upper side, and screens within the last mentioned opening and the opening in the upper end of the said neck portion.
2. A highway signal comprising a housing including a base portion, angle plates secured at their lower ends to the said base portion, and the sides of the said housing being secured to the flanges of the said angles, and also including a neck portion secured at its lower end to the upper ends of the said angle plates, said neck portion having an opening through its upper end, a signal head secured to the upper end of the said neck portion, and light producing means within the said housing and the said signal head.
3. A highway signal comprising a housing including body and neck portions the said neck portion terminating in an upwardly and outwardly flared extension and a head comprising a casing the lower por-

tion of which is secured to the upper end 35 portion of the said extension and the opposite faces of said casing being of opaque material and one of which is provided with an opening through which the signals are adapted to be displayed and the said faces 40 also being provided with additional light emitting openings of a character to indicate the subject of the signal.

4. A highway signal comprising a housing including body and neck portions, the neck portion terminating at its upper end in an inwardly extending flange, an extension member provided with an inwardly extending flange adjacent its lower edge which flange is secured to the flange at the 50 upper end of the said neck portion and the said extension member flaring upwardly and outwardly, a head comprising a casing which is secured to the said extension, the front and rear faces of said head casing being of opaque material and one of the said faces being provided with an opening through which the signals are displayed, a lens secured in said opening and the said face being provided with other openings 55 therein of a character to indicate the subject of the signal.

In testimony that I claim the foregoing as my invention, I have hereunto subscribed my name this 24 day of January, A. D., 65 1921.

ELOF H. MEDÉN.
